UNITED STATES PATENT OFFICE.

CARL RICHARD JERNBERG AND MODESTE ANDREW METZGER, OF CHICAGO, ILLINOIS,
ASSIGNORS TO STANDARD FORGINGS COMPANY, OF CHICAGO, ILLINOIS, A COR-
PORATION OF ILLINOIS.

FORGED-STEEL DRAFT-RIGGING ATTACHMENT.

Application filed March 30, 1921. Serial No. 456,985.

To all whom it may concern:

Be it known that we, CARL RICHARD JERNBERG and MODESTE ANDREW METZGER, citizens of the United States, residing at Chicago, in the county of Cook and State of Illinois, have invented certain new and useful Improvements in Forged-Steel Draft-Rigging Attachments, of which the following is a specification, reference being had to the accompanying drawings, and to the reference characters marked thereon, which form a part of this specification.

This invention relates to draft rigging for railway cars, and has for its object, more particularly, the construction or means for securing the rigging to the car sills and to the car coupler and to the draft gear or shock absorbing unit, whereby a more perfect action of the latter is secured.

Another object is to produce a draft rigging of such construction as to permit its several elements to be made of forged steel. Another object is to construct the several parts in such fashion as to permit them to be readily assembled and then held together by lugs and by an inserted key or bolt. Another object of the invention is to construct the parts so as to withstand the maximum of shock and reduce the wear which would otherwise follow, thereby prolonging the period of utility of the device.

To the accomplishment of these and other objects, the invention consists in the devices and combinations of devices illustrated, described and claimed herein.

In that form of our invention in which we have chosen to illustrate it, in the accompanying drawings:

Fig. 1 is a top plan view of our invention, as applied to a pair of conventionally shaped and disposed car sills, detached from the car structure.

Fig. 2 is a side elevation of the same, looking from a plane inside one sill toward the other sill, with some of the parts in section.

Fig. 3 is a front elevation, on a reduced scale, looking towards the car end on the line indicated at 3-3 in Fig. 2.

Fig. 4 is a horizontal, sectional view, taken in the plane of the line 4-4 of Fig. 2. Fig. 5 is a longitudinal, sectional view of the yoke head member, taken on the plane of the line 4-4 of Fig. 2. Fig. 6 is a transverse, vertical, sectional view of one of the yoke heads.

Figs. 7, 8 and 9 are side, top plan and front end views, respectively, of the yoke.

In said drawings, A, A represent a pair of draft sills for a car structure, being of standard channel section and extending longitudinally of the car in spaced apart, parallel relation; B, B represent front draft-gear stops; C, C the opposed or back draft gear stops; D a shock absorbing unit or draft gear as a whole; E the shank of the car coupler; F, a strike plate unit upon the end beam or channel G of the car structure; H the yoke heads; K, the draft key or pin, and Y is the yoke.

The strike plate F is secured transversely of the sills A, to the channel G, by rivets 1 as shown in Fig. 3. A strap member 2, riveted at its ends to the channel G and to the lower flanges 3 of the sills A, forms a suitable support for what we term a carrying iron 4 for the coupler shank E. The iron 4 in this instance, is bent up at its ends to fit within the sills A and is riveted at 5 to the strap 2.

The front draft-gear stops B, B, are secured to the inner or proximate faces of the sills A, A, by rivets 6, and the opposed stops C similarly secured to the sills by rivets 7. Intermediate these pairs of stops is a transversely disposed carrier strap 8 secured at its two ends by rivets 9 to the lower flanges 3 of the sills A; said strap 8 serving as a support or carrier upon which the draft gear unit D may rest and be supported. The carrier strap, in this instance, has a central, transverse depression or offset 10 to accommodate one arm of the yoke Y between the strap 8 and the unit D. The shock absorbing unit D may be of any conventional type and since, per se, it forms no part of the present invention except in combination, as a unit, with the other elements of our invention, it is not necessary to illustrate or describe it in detail. The illustration given may indicate a type of construction such for example, as that shown in the Christy Patent No. 1,263,374, of April 13, 1918, where the housing is hollow and contains springs acted upon by triangularly shaped wedges 11, which contact with a lower plate 12, the latter resting against the shoulders 13 of the front stops B, and the end of the housing of the unit D resting against the shoulders 14 of the back stops C. It

will be understood that there is relative movement between the parts, both on the draft and buff, the follower plate 12 and wedges 11 being pushed toward the unit D on the buff and the unit D traveling longitudinally towards the wedges under draft of the coupler yoke.

Referring now more particularly to Figs. 7, 8, and 9, it will be noted that the coupler yoke Y is U-shaped, having two long arms 15 united by an end member 16 and that the free ends of the arms 15 have a head of peculiar conformation, being both thicker and wider than the thickness and width of the arm 15. The yoke head and the yoke ends have complementary engaging parts which may be somewhat modified from the forms illustrated. As shown, each head has a raised flange 17 which extends across the width of the yoke arm 15, its inner face being recessed between its two straight ends. Thus on what may be termed the inner or draft gear D side, this central V-shaped flange has a bearing shoulder 18 and a straight bearing shoulder 19 at each end of the recessed part, each of said shoulders 18 and 19 having a straight, vertically disposed surface. The extreme outer end of the yoke arm 15 has a vertically arranged, straight face 20, the upper margin of which is joined to the flange 17 by a sloping curved wall 21. At a remove from the flange 17 and extending outwardly on each side arm 15, is a flange 22 having a bearing shoulder or face 23 that extends parallel with the surfaces 19. When a filler plate (indicated by dotted lines in Figs. 7 and 8) is used between the end 16 of the yoke and the end of the housing of the unit D, it may be secured to the yoke by a rivet passed through the aperture 24 in the end 16.

The front draft gear stops B, B, are tapered plates of gradually increasing thickness, terminating in a raised, transverse shoulder 13. Extending centrally from one end of the stop B and substantially at right angles to said shoulder, is a raised strengthening rib. Through the tapered plate B and its rib is an elongated slot or aperture adapted to receive a draft key K.

The opposed or rear draft gear stops C are tapered plates which gradually increase in thickness toward their front ends; the front face or shoulder 14 of said stops being straight and vertically disposed to receive the end of the gear unit D.

The two yoke heads H are required, one for each side of the coupler shank. The heads are each provided with surfaces complementary in configuration to surfaces on the end of the yoke arms 15, so that when they are placed in position on each side of the yoke, the yoke arms and heads are firmly interlocked, the lugs on the yoke head being on the top and the bottom surfaces of the yoke arm. The key K is passed horizontally

through the two front stops B and each of the yoke heads H as well as the intermediate coupler shank E.

It will thus be observed that the yoke heads and the coupler travel in unison with the yoke Y and that the latter, therefore, has relative movement with respect to the housing of the draft gear unit D. The arms 15 of the yoke Y being relatively wide have a larger frictional surface bearing upon the housing of the draft gear unit D, which is an important practical feature of the invention.

Referring to Figs. 5 and 6, more particularly, it will be seen that the head H has a straight body portion 38, provided at top and bottom with inturned flange members 39, which latter, when the parts are assembled, extend above and below the yoke ends and contact with said yoke ends. The back margins of the flange members 39 are straight and are adapted to bear against the front straight surface of the yoke lug 22, as clearly seen in Figs. 1 and 2; while their front faces or margins incline downwardly from the body H, as illustrated, to fit within the bearing shoulder 18 of the yoke flange 17. The body part 38 is provided at its front with a forwardly extending, thickened and apertured retaining lug 41, which is braced by and united at its side margins with the body part 38 by strengthening webs 42. The aperture 43 which extends through the arm 41 conforms in shape to the aperture 27 of the stop B, though it is not so long. The key K fits snugly in the aperture 43, as shown in Figs. 2 and 4, and is of a length sufficient to span the distance between the sills A, passing through as it does, the two sills, the front stops B, B, the yoke heads H, H, and the yoke shank E, the latter and the sills being suitably apertured for the purpose. The key K has a flanged head 44 at one end and at the other end is provided with a washer 45 held in place by a cotter pin 46 which passes through an aperture 47 in the key K.

The straight shoulder surfaces 19 of the yoke flange 17 contact with the straight shoulder surfaces 48 of the flange 39, when the parts are in the assembled position shown in Figs. 1 and 2.

It will be noted that each of the parts is so shaped and constructed as to permit of its being fabricated by forging out of steel, thus making a very substantial, durable, relatively cheap device, which will not get out of order.

What we claim is:

1. A draft rigging attachment comprising a U-shaped yoke of forged metal, the inner faces of its two arms being straight and parallel throughout, said yoke being adapted to embrace a gear unit, the free ends of said

- arms extending beyond the forward end of said unit, an integral, transverse, outwardly projecting shoulder flange on each of the free ends of the yoke arms, two forged metal yoke head members adapted to embrace a coupler shank and said yoke ends, and complementary, interlocking means on said yoke head members to engage said shoulder flanges.
10. 2. A draft rigging attachment comprising a forged metal U-shaped yoke adapted to embrace a gear unit with its free ends extending beyond the forward end thereof, and having an outwardly extending shoulder flange on each free end extending transversely of and substantially across each yoke end, two horizontally apertured, forged metal, yoke head members adapted to embrace a coupler shank and said yoke ends and complementary, interlocking means on said yoke head members adapted to engage said shoulder flanges.
3. The combination with a draft gear unit and a coupler, of a draft rigging attachment comprising a U-shaped yoke of forged metal extending about two sides and the ends of said unit and provided at each free end with an outwardly extending, integral, transverse flange, the rear face of which constitutes a shoulder which extends substantially the width of the yoke end, a pair of forged metal yoke heads adapted together to embrace the coupler shank, each head provided with two flange members adapted for interlocking engagement with the yoke end flanges, and a key extending laterally through the two sets of flange members and the coupler shank.
4. The combination with a draft gear unit and a car coupler, of a draft rigging attachment comprising a forged metal U-shaped yoke extending about the two sides and the end of said unit and provided upon each free end with a raised flange, extending transversely across the free end, a pair of forged metal yoke heads adapted together to embrace the coupler shank, each head having two flange members adapted for interengagement with the yoke end flanges, each of said yoke heads being slotted horizontally to receive a locking draft pin or key.
5. A draft rigging attachment comprising a forged metal U-shaped yoke adapted to embrace a gear unit, the free ends of the yoke side members extending beyond the forward end of said unit, the inner faces of the yoke side members being straight and parallel throughout, an integral flange extending transversely on the outside of each side member, its rearwardly directed face constituting a shoulder which extends substantially the width of the yoke member, a pair of forged metal, independent yoke heads for uniting the yoke ends with a coupler shank, and complementary, interlocking means on the yoke heads and yoke ends whereby the two will travel in unison over a draft gear box or housing.
6. A draft gear rigging attachment comprising a forged metal yoke adapted to embrace a draft gear unit, with its free ends extending beyond the unit, each yoke end having a transverse, rearwardly directed shoulder substantially equal in length to the width of the yoke, combined with a pair of forged metal, independent yoke heads having complementally formed recesses, whereby said yoke heads and said yoke ends are interlocked and have relative movement as a unit with respect to the draft gear unit, a key receiving slot in the yoke heads and means for uniting the yoke heads to a coupler shaft.
7. A draft gear attachment comprising a forged metal, U-shaped yoke of the vertical type, adapted to embrace a draft gear unit, each of the free ends of its two arms being provided with an outwardly projecting integral flanged shoulder extending transversely of the yoke arm, and a pair of independent yoke plates, each having a laterally extending, inturned flange member at its top and its bottom, the front faces of the inturned flange members being forwardly inclined to bear against the yoke flanged shoulder when the yoke and said independent plates are assembled, said plates being also provided with a horizontal key receiving slot.
- In testimony that we claim the foregoing as our invention, we affix our signatures in the presence of two witnesses, this 26th day of March, 1921.
